UNITED STATES PATENT OFFICE

2,591,468

SUPPORT FOR CUP TYPE MOP WRINGERS

Bernard E. Rorem, Dayton, Ohio

Application September 25, 1946, Serial No. 699,101

2 Claims. (Cl. 248—110)

1

My present invention relates to improvements in mop wringers of the type involving a drainage passage-equipped wringer cup adapted to be mounted on a suitable mop pail or receptacle, and wherein a mop is inserted and placed under pressure to express excess liquid from the mop; the excess liquid flowing through the drainage passages in the cup and into the underlying pail or receptacle. More particularly, the present invention relates to an improved means for quickly and detachably attaching or anchoring such mop wringers to cooperating mop pails or the like.

A still further object of the present invention is the provision of an improved means for detachably anchoring the mop wringer of the class described to the upper edge portion of a cooperating pail or other receptacle without boring any holes in, or otherwise defacing, the pail or other receptacle, and without the use of auxiliary clamping or anchoring devices, such as screws, bolts, or the like.

Still another important object of the invention is the provision of an improved anchoring device of the general character immediately above described which can be readily adapted to fit cooperating mop pails of different diameters.

A still further important object of the invention is the provision of an improved device for anchoring a mop wringer of the class described to the upper edge portion of a cooperating mop pail or receptacle, which is extremely simple, can be constructed at very low cost, and can be quickly and easily applied to the wringer cup on one hand and to the cooperating pail on the other hand.

A still further object of the invention is the provision of an improved anchoring device or means for mop wringers of the kind described which can be shipped together with a mop wringer in disassembled or knock-down form and be readily assembled and applied to the cooperating mop wringer by the ultimate purchaser.

The above and other highly important objects and advantages of the invention will be made apparent from the following specification, claims, and appended drawings.

In the accompanying drawings, like characters indicate like parts throughout the several views.

Referring to the drawings:

Fig. 1 is a perspective view illustrating a mop wringer of the class described detachably anchored to the top of a cooperating receptacle in the nature of a mop pail through the medium of a preferred embodiment of the instant invention;

2

Fig. 2 is a greatly enlarged fragmentary sectional view taken approximately on the line 2—2 of Fig. 1;

Fig. 3 is an enlarged fragmentary detail view 5 in side elevation looking from left toward the right in respect to Fig. 2;

Fig. 4 is a horizontal sectional view taken on the line 4—4 of Fig. 3;

Fig. 5 is a fragmentary sectional view in side 10 elevation taken approximately on the line 5—5 of Fig. 4; and

Fig. 6 is a fragmentary view corresponding to Fig. 5, but showing a slightly modified form of wringer anchoring means.

15 The mop wringer herein illustrated for the purpose of example is of the kind disclosed and claimed in my co-pending application, Serial No. 699,100, now abandoned, filed of even date herewith. This mop wringer comprises a drainage passage-equipped cylindrical wringer cup 1 which is closely and finely perforated to provide the desired drainage passages and is provided at its top with an upwardly or outwardly-flaring mop-guiding skirt 2 and at its 20 intermediate portion with an outwardly-pressed circular bead 3. In Fig. 1, a mop is shown in approximately operative position within the wringer cup 1, and this mop, which is of the commercial circular type, comprises a mop head 4 and a suitable handle 5. The receptacle on which the wringer cup 1 is mounted through anchoring means of the present invention is in the nature of a conventional mop pail indicated as an entirety by 6, said pail being provided 25 with an outwardly-rolled rim 7 at its upper edge and being also provided with the usual bail pivotally secured thereto through the medium of anchoring arms 9.

With reference first to Figs. 1—5 inclusive, the 30 wringer cup anchoring means comprises a pair of relatively long anchoring arms 10 and a relatively short anchoring arm 11, said anchoring arms 10 and 11 all being mounted on the wringer cup and projecting laterally therefrom and the 35 said short arm 11 being approximately equally circumferentially-spaced between the opposite arms 10. Preferably, and as herein illustrated, the opposite anchoring arms 10 are integrally-formed from a common bar or strip, indicated as an entirety by 12, and are connected by an intermediate segmental portion 13 of said bar 12 that closely embraces and matches the exterior contour of the cylindrical wringer cup 1. The 40 entire arm-forming bar 12 is rigidly, but detachably, anchored to the longitudinally-inter-

mediate portion of the wringer cup 1 by a pair of segmental clamping bands 15 and 16 respectively, and the said short anchoring arm 11 is formed integrally with and as a radially outwardly-turned extension of the clamping band 16. The segmental clamping bands 15 and 16 are detachably connected to the bar 12, from which the arms 10 are formed, by hook-like anchoring tabs 15' and 16' formed on adjacent ends of the bands 15 and 16, and which are passed through receiving apertures 15'' and 16'' in the bar 12 adjacent the inner ends of the opposite arms 10. The other end of the clamping band 15 is provided with a radially out-turned anchoring flange 17 in spaced parallel relation to the short anchoring arm 11 and screw-threaded clamping means in the nature of a nut-equipped clamping bolt or the like 18 is passed through aligned apertures in the flange 17 and short arm 11 to clamp the bands 15 and 16 tightly about the wringer cup 1. The segmental clamping bands 15 and 16, together with the clamping bolt 18 and the intermediate portion 13 of bar 12 comprise a clamping band of the well-known split variety.

Adjacent their free ends, the arms 19 and 11 are formed to provide centering shoulders 10' and 11', respectively, and outwardly adjacent said centering shoulders the lower edges of the arms 10 and 11 define upper pail bead-engaging seat 27. Outwardly of the said upper seats 27 the arms 10 and 11 are formed with anchoring hooks; the hook of arm 11 being indicated by 19, the hook of one of the arms 10 by 20, and the hook of the other arm 10 by 21. The hooks 19, 20, and 21 are turned backwardly and downwardly with respect to their respective arms, so that the free end portions thereof define lower pail bead seats 28 for engagement with the lower surface of the pail bead 7. The lower seats 28 are located in a horizontal plane below the plane of the upper seats 27 and are laterally offset therefrom. The lower seats 28 of hooks 19 and 20 are offset each in the direction of the other hook 19 or 20 and the seat 28 of hook 21 is offset in the direction of the hook 19. The anchoring hook 21, as will be seen particularly by reference to Figs. 3 and 4, is provided at its free end portion with an integrally-formed outturned handle 22 to facilitate application of the device to a cooperating pail or the like.

The mop wringer may most conveniently be packaged for shipment with the anchoring device described in disassembled or knock-down form, but due to the simplicity of the construction described, the matter of assembling the parts may be readily accomplished by the ultimate purchaser, who needs only insert the hooks 15' and 16' through the apertures 15'' and 16'' respectively, insert the mop cup within the confines of the segmental clamping bands 15 and 16, and apply the nut-equipped clamping bolt 18. With this done, the matter of attaching the mop wringer to a conventional mop pail, such as herein indicated by 6, is easily and quickly accomplished in the following manner, to wit: The anchoring hooks 19 and 20 are first hooked under the rim 7 of the pail. With this done, the free end portion of hook 21 will rest on the upper side of the pail bead 20, assuming that the arms 10 are of proper length for the particular pail involved. Now, to accomplish the anchoring of the mop wringer to the mop pail, it is merely necessary to apply sufficient downward pressure

to the hook 21 through the medium of the handle 22 thereof to force the same around and under the rim 7 of the pail; this being accomplished by slight springing of the hook 21, rim 7, or a combination of both. In case it is found that the arms 10 are so long as to space the hook 21 outwardly of the rim 7, the arms 10 and 11, which are initially straight, may be bent by hand to produce an effective shortening of the arms as measured on a straight line from their ends to their respective hooks. In fact, in the drawings, the initially straight arms 10 are shown as having been bent or warped to accomplish the desired foreshortening to fit the anchoring device of a mop wringer to the particular pail involved. It will, of course, be understood that the arms 10 and 11 are formed of relatively soft or ductile metal, so that they may be rather easily bent by hand and will tend to remain in the bent position.

By reference to the drawings, it will be seen that the bead 3 of the wringer cup 1 is seated against the upper edges of the clamping bands 15 and 16, so as to restrain the mop cup against downward movement under pressure exerted on the mop through the mop handle 5.

The modified form of the invention shown in Fig. 6 differs from the embodiment of the invention shown in Figs. 1-5 inclusive only in the manner in which the segmental clamping bands 15 and 16 are secured to the bar-like element 12; and in Fig. 6, parts corresponding to parts in Figs. 1-5 inclusive are indicated by like characters. In Fig. 6, the bar 12 is provided adjacent the inner ends of its arm-forming portions 10 with elongated slots 23 and 24 which replace the circular apertures 15'' and 16'' of Figs. 1-5 inclusive, and the clamping bands 15 and 16 are respectively provided with head-equipped anchoring tabs 25 and 26 that replace the anchoring hooks of Figs. 1-5 inclusive. The slots 23 and 24 are of just sufficient length and width to receive the heads of tabs 25 and 26 respectively, and the said head-equipped tabs, being turned 90° after insertion through the slots, become positively interlocked with the bar 12. This system of locking the elements together is particularly desirable when the metal employed is so light that the hooked tabs of the other figures might tend to straighten out and become disengaged under clamping pressure.

The segmental bands 15 and 16, together with the segmental portion 13 of bar 12, jointly form what may be hereinafter referred to alternately as a circular clamping band or split circular clamping band.

What I claim is:

1. A device for anchoring wringer cups to rim-equipped mop pails, said device comprising an anchoring band adapted to receive a wringer cup and having three circumferentially-spaced anchoring arms projecting therefrom, said arms being of relatively thin flat band stock disposed with their narrow edges one above the other, the outer portions of the under edges of said arms providing upper pail bead seats, said arms being formed outwardly of said upper seats with anchoring hooks, the free end portions of the upper edges of which provide cooperating lower pail bead seats disposed below the plane of the upper bead seats and laterally offset from their respective cooperating upper bead seats.
2. A device for anchoring wringer cups to rim-

equipped mop pails, said device comprising an anchoring band adapted to receive a wringer cup and having three circumferentially-spaced anchoring arms projecting therefrom, said arms being of relatively thin flat band stock disposed with their narrow edges one above the other, the outer portions of the under edges of said arms providing upper pail bead seats, said arms being formed outwardly of said upper seats with anchoring hooks, the free end portions of the 10 upper edges of which provide cooperating lower pail bead seats disposed below the plane of the upper bead seats and laterally offset from their respective cooperating upper bead seats, the lower bead seats of two adjacent arms, being laterally 15 offset from their respective cooperating bead seats each in the direction of the other said arm.

BERNARD E. ROREM.
